Primary Examiner — Susan Bennett Hattan*Assistant Examiner* — Leanne Was(74) *Attorney, Agent, or Firm* — Ash Tankha; Lipton, Weinberger & Husick(57) **CLAIM**

The ornamental design for a integrated bottle top apparatus assembly, as shown and described.

DESCRIPTION

FIG. 1 is an elevation view of an integrated bottle top apparatus assembly;

FIG. 2 is a top perspective view thereof;

FIG. 3 is an enlarged top perspective view thereof;

FIG. 4 is a right side exploded view thereof; and,

FIG. 5 is a right side orthogonal exploded view thereof.

The broken lines in the drawing depict environmental subject matter only and form no part of the claimed design.
